UNITED STATES PATENT OFFICE.

HENRY CROWTHER AND CHARLES TIMM, OF PITTSBURG, PENNSYLVANIA.

DESIGN FOR A BICYCLE-FRAME.

SPECIFICATION forming part of Design No. 30,969, dated June 6, 1899.

Application filed March 1, 1897. Serial No. 625,667. Term of patent 7 years.

To all whom it may concern:

Be it known that we, HENRY CROWTHER and CHARLES TIMM, citizens of the United States, residing at Pittsburg, in the county of Allegheny and State of Pennsylvania, have invented and produced a new and useful Design in Bicycle-Frames, reference being had to the accompanying drawings, forming a part thereof.

10 In the accompanying drawings, Figure 1 is a perspective view of our design, and Fig. 2 a cross-sectional view taken on line 2 of Fig. 1.

The leading feature of our design consists in a main portion of the frame provided with 15 a lower Y-shaped rear portion and an upper Y-shaped rear portion joined together at and near their free ends, the members of which are D-shaped in cross-section.

A is the main portion, comprising the parts

B, C, and D. E is the lower Y-shaped rear portion having a single cylindrical stem e and the Y proper or bifurcated portion e'. G is the upper Y portion, comprising the cylindrical stem g of the Y portion proper or bifurcated portion g', the members of which are 25 D-shaped in cross-section and joining the lower portion at H, the whole presenting to the eye a harmonious and ornate figure, as illustrated in the drawings.

We claim—

30 The design for a bicycle-frame herein shown and described.

HENRY CROWTHER.
CHARLES TIMM.
